Attys.

UNITED STATES PATENT OFFICE.

JOHN E. PERTL, OF PALMS, CALIFORNIA.

DUSTLESS ASH-SIFTER.

1,295,058.

Specification of Letters Patent. Patented Feb. 18, 1919.

Application filed May 31, 1918. Serial No. 237,583.

To all whom it may concern:

Be it known that I, JOHN E. PERTL, a subject of the Emperor of Austria, residing at Palms, in the county of Los Angeles and 5 State of California, have invented new and useful Improvements in Dustless Ash-Sifters, of which the following is a specification.

My object is to make a dustless ash sifter and consists in the novel features herein 10 shown, described and claimed.

Figure 1 is a top plan view of a dustless ash sifter embodying the principles of my invention, parts being broken away.

Fig. 2 is a cross-section on the lines 2—2 15 of Figs. 1 and 3.

Fig. 3 is a vertical longitudinal section on the lines 3—3 of Figs. 1 and 2.

Fig. 4 is an enlarged fragmentary sectional detail on the line 4—4 of Fig. 2.

20 Fig. 5 is an enlarged fragmentary sectional detail on the line 5—5 of Fig. 1.

Fig. 6 is an enlarged detail of a piece of the sprinkler pipe.

The main body of the ash sifter is a 25 rectangular box comprising vertical walls 1, 2, 3 and 4 formed of sheet metal and mounted upon legs 5. A bottom 6 is mounted within the walls 1, 2, 3 and 4 and fills substantially one-half of the space, the other half of the 30 space being occupied by an opening 7. A slide 8 is inserted through the wall 4 above the bottom 6 to close the opening 7. An inclined baffle plate 9 is secured to the wall 4 some distance from the bottom and extends 35 inwardly and downwardly toward the opening 7. A bracket 10 extends downwardly from the center of the slide 8, and retractile coil springs 11 and 12 are connected to the bracket 10 and extend diagonally to the rear 40 corners and are attached to the rear corner legs 5, the tensions of the springs being exerted to hold the slide 8 in its closed position and said springs pulling laterally in opposition to each other with equal tension so as to 45 prevent the slide from binding on the sides. An inclined chute 13 leads through the upper part of the wall 1, there being a flat door 14 connected at its upper side by a hinge 15 to the outer end of the chute, so that the door 50 will close by gravity and so that the door will swing open when cinders pass down the chute 13.

A sifter pan 16 fits loosely in the upper part of the box and has a spout 17 discharging into the chute 13. Trunnions 18 and 19 extend outwardly from the sides of the sifter

pan near their rear ends, that is, near the spout 17. Bearing plates 20 and 21 are fixed to the inner faces of the walls 2 and 4 and said plates have slotted bearings 22 to receive 60 the trunnions 18 and 19 so as to pivotally mount the sifter pan. The sifter pan 16 has a screen bottom 23. The sifter pan 16 is held in its horizontal position by resting upon the trunnions 18 and 19 in the plates 20 and 21 65 and the top of the spout 17 bearing upwardly against the top of the chute 13.

A hopper 24 extends upwardly from the upper edges of the walls 1, 2, 3 and 4, a cover 25 is connected to one side of the hopper by 70 hinges 26, and a folding link 27 connects the cover 25 to the hopper, so that when the cover is raised to a vertical position and overbalanced slightly the link 27 will support the cover.

A crank shaft 28 is mounted in a bearing 29 carried by a bracket 30 and the bracket 30 is secured to the upper part of the wall 3. A crank wheel 31 is fixed upon the outer end of the shaft 28 and a crank handle 32 is fixed 80 to the crank wheel for manually operating the wheel. The wheel 31 serves as a fly wheel. A cam 33 is fixed upon the inner end of a cam shaft, said cam shaft extending through a bearing 34 and said bearing 34 extending 85 through the wall 3, and gears 36 and 37 connect the crank shaft 28 to the cam shaft, so that when the handle 32 is manually operated the cam 33 rotates, and the cam face 38 upon the cam 33 is rounded and a segment 90 of a circle and is adapted to engage the bottom of the sifter pan 16 at the extreme forward end, that is, the opposite end from the spout 17, so that as the handle 32 is operated to rotate the cam the cam will shake the 95 free end of the sifter pan 16 up and down as required to sift the ashes in the pan, and the dust and ashes will pass downwardly through the screen 23 into the chamber 39 of the box. A handle 40 extends upwardly 100 from the sifter pan 16 so that when the ashes have been sifted out of the cinders the handle 40 is manually operated to raise the free end of the sifter pan, and tilt the pan upon the trunnions 18 and 19 to discharge the cinders through the spout 17 to the chute 13. A pail or coal-hod may be placed under the chute to receive the cinders.

A check-valve casting or block 41 is placed against the inner face of the wall 3 and the 110 nipple 42 of a stop-cock 43 is screwed through the wall 3 into the block 41. The

2
 water pipe 44 is attached to the stop-cock 43. A horizontal passage 45 leads from the nipple 42 to a vertical passage 46, there being a valve seat 47 at the upper end of the vertical passage 46. A passage 48 leads from above the valve seat 47 and the sprinkler pipe 49 leads from this passage 48. The sprinkler pipe 49 extends around three sides of the box and has slits forming nozzles 50 discharging horizontally inwardly. The valve member 51 fits upon the seat 47 and has a stem 52 extending downwardly through the block 41. A spring casing 53 is screwed into the block 41 from the top and a spring 54 in the casing 53 engages the valve 51 to hold it yieldingly upon the seat 47, the tension of the spring being sufficient to hold the water pressure coming through the stop-cock 43. The tip 55 of the stem 52 extends some distance below the block 41. A lever 56 is pivotally mounted in a horizontal position against the inner face of the wall 3 upon a bracket 57 and pivot pin 58. The pivot pin 58 is substantially at the center of the lever 56. A roller 59 is carried by one end of the lever 56 in position to be engaged by the cam face 38, and the opposite end 60 of the lever is in position to engage the tip 55 of the valve stem, so that when the stop-cock 43 is open and the sifting operation is being carried on the cam face 38 will engage the roller 59 at each revolution of the cam and press the roller 59 downwardly, thereby pressing the end 60 of the lever upwardly to unseat the valve 51 and allow water to shoot through the sprinkler pipe 49 and through

the nozzles 50 so as to sprinkle the interior of the chamber 39 and settle the ashes and dust. The wet ashes and dust will fall upon the slide 8 and the baffle 9 until a sufficient quantity has been accumulated and then the handle 61 of the slide 8 is grasped to pull the slide against the tensions of the springs 11 and 12 to uncover the opening 7 and allow the wet ashes and dust to fall through the opening.

Various changes may be made in the details of construction without departing from the spirit of my invention as claimed.

I claim:

1. In a dustless ash sifter, a sifter pan, a cam for shaking the sifter pan, a hand-crank for operating the cam, a water pipe, a check-valve in the water pipe, a sprinkler connected to the check-valve and located below the sifter pan, and means whereby the cam intermittently opens the check-valve.

2. In a dustless ash sifter, a sifter pan, means for shaking the same, a sprinkler located below the sifter pan, and means operatively connected to said pan shaking means for operating the sprinkler.

3. In a dustless ash sifter, a sifter pan, means for shaking the sifter pan, a water pipe, a check-valve in the water pipe, a sprinkler connected to the check-valve and located below the sifter pan, and means operatively connected to said pan shaking means for intermittently opening the check-valve.

In testimony whereof I have signed my name to this specification.

JOHN E. PERTL.
